UNITED STATES PATENT OFFICE.

CLAUDE L. POST, OF CHICAGO, ILLINOIS.

ENVELOPE-FEEDING MECHANISM.

Application filed September 28, 1923. Serial No. 591,107.

To all whom it may concern:

Be it known that I, CLAUDE L. Post, a citizen of the United States, residing at Chicago, in the county of Cook and State of Illinois, have invented certain new and useful Improvements in Envelope-Feeding Mechanisms, of which the following is a description.

My invention relates to improvements in envelope feeding mechanisms, and particularly to such a mechanism for use in conjunction with a printing press or the like, wherein it is desired to feed sheets, envelopes, etc., at a high rate of speed and yet have said sheets fed through the press in absolute registry with the printing rolls.

One of the objects of my invention is to provide means for centering the sheets as they are fed between the printing rolls.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is a side elevation of an improved device;

Fig. 2 is a top plan view thereof;

Fig. 3 is a sectional view taken substantially on the line 3—3 of Fig. 2;

Fig. 4 is a plan view of the center device itself;

Fig. 5 is a sectional view taken substantially on the line 5—5 of Fig. 4;

Fig. 6 is a side view of the device shown in Fig. 4;

Fig. 7 is a sectional view taken substantially on the line 7—7 of Fig. 4;

Fig. 8 is a sectional view taken substantially on the line 8—8 of Fig. 4;

Fig. 9 is an enlarged fragmentary plan view of the platen and type rolls showing the means for preventing contact therebetween when there is no envelope passing between the rolls;

Fig. 10 is a sectional view taken substantially on the line 10—10 of Fig. 9;

Fig. 11 is a sectional view taken substantially on the line 11—11 of Fig. 9; and 55

Fig. 12 is a sectional view taken substantially on the line 12—12 of Fig. 10.

In the preferred form of construction, as shown in the drawings, I have shown the device as used in connection with a press 60 for feeding envelopes from a magazine, conveying them between a pair of printing rolls and discharging them in a pile at the rear end of the press. It is to be understood, however, that my device is not only adapted 65 to be used for envelopes, but it may be used for feeding any other similar objects or materials, such as sheets or the like.

1 represents a supporting frame for the mechanism, the same being adapted to be 70 suitably supported by or mounted upon a cooperating structure so that it will be of the right height for most efficient operation. In this device the envelopes are retained in a magazine or the like, and are fed one at a 75 time automatically through printing rolls and are then automatically discharged and stacked up for removal. The printing rolls comprise a pair of rolls 2 and 3 respectively, the former being the type roll and the 80 latter the platen, and through which the envelopes or sheets must pass to be imprinted. These rolls are driven positively in unison through any form of gearing or the like, and in any desired manner, both of said rolls 85 rotating at the same rate of speed. It is to be noted, however, that the platen roll 3 has the ends of its shaft 4 mounted in eccentrically bored bushings 5, as shown more clearly in Figs. 9 and 10, for a purpose to be 90 more clearly hereinafter described.

The magazine 6 is preferably removably arranged on the frame at a distance away from the printing rolls 2 and 3, and a finger 7 operated in any desired manner is positioned adjacent the discharge end of the magazine to engage the flaps of the envelopes and extend them forwardly toward the printing rolls so that they may be frictionally held between the peripheral surfaces of 100 the feed rolls 8 and 9, respectively, and pulled therethrough in the direction of the printing rolls, said feed rolls 8 and 9 being also positively driven.

Intermediate the printing rolls and the 105 feed rolls there is arranged means for posi-

tively conveying the envelopes as they are discharged from the feed rolls and delivering them to the printing rolls while at the same time centering the envelopes so that they will be in the correct position for printing as they are fed into the printing rolls. This last-mentioned mechanism comprises a framework having substantially parallel lateral bars 11 and 12 at the ends thereof adjacent the printing rolls and feed rolls respectively. Envelope supporting bars 13 extend between the bars 11 and 12 laterally thereto and upon which the envelopes are adapted to slide. Channel guide members 14 are arranged laterally of the bars 11 and 12 and project therebeyond at both the ends and are adapted to receive the side edges of the envelopes as they are conveyed from the feed rolls to the printing rolls, as shown more clearly in Fig. 4.

In order to accommodate the different sizes of envelopes which may be met with in ordinary use, the bars 14 are adjustably connected to the bars 11 and 12 at their ends as at 15 and 16 respectively. The channel bars 14 preferably diverge or are spaced apart a greater distance at the ends adjacent the feed rolls than at other points therewith, and the discharge ends of said channel bars are spaced apart a distance equal to the length of the envelopes fed therethrough. In this manner the envelopes will enter between the channel bars without hindrance and come into exact registry or center as they are discharged from the channel bars and fed between the printing rolls.

In order to more positively actuate the envelopes during their travel between the feed rolls and type bars, belt conveyors 17 are arranged beneath the centering frame and have lugs 18 spaced thereon at suitable intervals to engage the rear edges of the envelopes and push them along. Adapted to cooperate with the roll 9, and drivingly connected therewith by a belt 19, is a roll 20, whereby the envelopes are pressed downwardly and firmly held on the conveyor belts during their travel. Short bars 21 are arranged parallel to the bars 13 and spaced a short distance thereabove at the discharge end of the centering device, as shown in Figs. 3 and 4, said bars preferably having their inner ends up-turned so as to prevent any interference with the envelopes. A spring member 22, having a curved end 23, is mounted upon the cross bar 11, so that its curved end 23 will bear on the envelopes being discharged from the centering device retarding the envelope and hence allowing feeding guide to fully act.

The member 22 is mounted so that the tension thereof may be varied, there being a coil spring 24 positioned intermediate the bar 11 and the end of the member 22 connected thereto.

In order that the type roll and printing roll shall not come together whenever there is no envelope being fed therethrough, the shaft 4 is mounted in eccentric bushings 5, as has been heretofore described. Connected to one of said bushings, as shown in Figs. 3, 9 and 10, is a lever 25, so that when the lever is rocked or pivoted, the bushing will be oscillated to lower the rotational axis of the shaft 4 and thus separate the rolls 2 and 3.

In order that the eccentric journals at both ends of the roll 3 may be actuated simultaneously, a gear segment 26 is operatively connected to the lever 25 and is adapted to mesh with a pinion 27 of a shaft 28 mounted at the sides of the frame, the other end of the shaft 28 having a pinion thereon similar to the pinion 27 and intermeshing with a gear segment rigidly connected to the eccentric bushing at that end of the shaft 4. A cam member 28 is drivingly connected to the shaft of the roll 2, but is slidable longitudinally thereof, said cam being of such a contour that it will operate the lever 25 when rotating in the same plane therewith. An abutment or stationary cam 29 is carried on the frame 1 to engage the rotary cam 28 and retrieve said cam out of registry with the lever 25, but guiding said cam into registry therewith whenever said cam is slid longitudinally of the shaft of the type roll (to the right). A coiled spring 30 is interposed between the rotary cam 28 and the adjacent end of the type roll, in order to constantly urge said rotary cam to the right and into operative engagement with the lever 25.

In order to permit the spring 30 to operate only when there is no envelope being fed between the printing rolls, a pin 31, having an enlarged head 32 at its end, is rigidly carried by the cam 28 and projects inwardly of the inner side thereof, said enlarged head having a pair of substantially parallel beveled surfaces at its sides for a purpose to be more clearly hereinafter described.

A rocker shaft 33 is mounted within the roll 2, the same having at one end a fork 34, whose prongs are beveled at their inner opposed surfaces to correspond with the beveling of the parallel sides of the enlarged head 32 of the pin 31, said shaft 33 carrying a lever arm 35 at its other end, as shown in Fig. 11. The arm 35 is mounted so as to be movable inwardly below the envelope-contacting surface of the roll 2, and to be moved to project outwardly beyond said contacting surface whenever there is no envelope being fed between the rolls. A spring 36 may be positioned at some suitable point, as for instance at the fork 34, in order to normally urge the fork and lever arm 35 outwardly if so desired.

although generally centrifugal force will urge the fork outwardly.

The operation of the means for separating the printing rolls is as follows:

5. Referring to Figs 9 to 12 inclusive, the parts being in the position shown in full lines, let us assume that there is no envelope in readiness for insertion between the printing rolls. The spring 30 constantly presses 70 the rotary cam toward the stationary cam 29, said cam 28 being free to move toward the right, because the enlarged head 32 of the pin 31 is in position to permit such sliding movement through the fork 34. The 75 continued rotation of the cam 28 will cause it to slide off the cam 29 and engage with the rocker arm 25 actuating it to cause the separation of the rolls, the cam 28 again engaging the cam 29 and pushed back out of 80 registry with the arm 25, the parts all resuming their full-line position again after each separation of the rolls. A spring 37 may be positioned to engage the rocker arm 25 to return it to its normal position after 85 each actuation thereof. As soon as an envelope is in position for insertion between the rolls, the arm 35 will strike said envelope and be moved inwardly to its dotted-line position, thereby rocking the part 34 to 90 interlock it with the pin 31, as shown in dotted-line position in Fig. 12, so as to prevent the spring 30 from sliding the cam 28 to the right. Thus in each rotation of the 95 printing rolls the parts assume the full-line positions shown in the figures, so that the cam 28 may be moved to the right in case there is no envelope between the rolls, or that the arm 35 may be pressed inwardly to lock the cam 28 against movement in case 100 there is an envelope in position.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In combination with means for holding a supply of envelopes and printing rolls spaced therefrom, of means for positively feeding said envelopes successively from said supply and conveying them to said rolls, means intermediate said rolls and supply for aligning and centering said envelopes while being conveyed, and means frictionally engaging and retarding said 110 sheets as they are discharged from said centering means.

2. In combination with a pair of rolls and means for conveying sheets thereto, of means for centering said sheets as they are 115 moved therealong, stationary means for

slidably supporting said sheets while being conveyed, drive means for frictionally engaging said sheets to move them forwardly and press them onto said stationary supporting members, and tension members engaging said sheets as they are discharged from said centering device into said rolls.

3. In combination with means for holding a supply of sheets and printing rolls, of means for feeding said sheets successively from said supply to said rolls, means intermediate said rolls and supply for aligning and centering said sheets, means for maintaining the sheets against lateral movement while in said aligning means, and adjustable tension means engaging said sheets as they are discharged to said rolls from said aligning means.

4. In combination with means for holding a supply of sheets and printing rolls spaced therefrom, of means for positively feeding said sheets successively from said supply to said rolls, channel guides for slidably receiving the outer edges of said sheets and terminating adjacent said rolls, friction means engaging the sheets for maintaining them in said guides, and adjustable tension means engaging and retarding said sheets as they are discharged from said guides and enter between said rolls.

5. In combination with an envelope magazine, printing rolls spaced therefrom, and means for withdrawing envelopes successively from said magazine with their flaps open, of means for conveying said envelope from said last-mentioned means to said rolls, guides slidably receiving the side edges of the envelopes while being conveyed, means for maintaining said envelopes in said conveyor, and means for frictionally engaging and retarding said envelopes as they are being discharged from said conveyor into said rolls.

6. In combination with an envelope magazine, printing rolls spaced therefrom and means for withdrawing envelopes successively from said magazine with their flaps open, of means for conveying said envelopes from said last-mentioned means to said rolls, guides slidably receiving the side edges of the envelopes while being conveyed, means for laterally adjusting said guides, means for maintaining said envelopes against accidental shifting in said conveyor, means for yieldably engaging said envelopes to retard them as they are being discharged from said conveyor into said rolls, and means for adjusting the tension of said last-mentioned means.

7. In combination with a pair of printing rolls and means for conveying sheets to said rolls, of a frame intermediate said printing rolls and the point of entry of said sheets into said conveying means for centering said sheets as they are moved

- therealong, said last-mentioned means comprising a frame having substantially parallel bars spaced thereon, guide channel bars spaced apart laterally of said bars and adjustably secured thereto at each end so that their distance apart may be varied at either end, stationary means for slidably supporting said sheets while being conveyed, drive means for frictionally engaging said sheets to move them forwardly and press them onto said stationary supporting members, and tension means engaging said sheets as they are discharged from said centering device into said printing rolls.
- 10 8. In combination with means for holding a supply of envelopes and printing rolls

spaced therefrom, of means for positively feeding said envelopes successively from said supply and conveying them to said rolls, means intermediate said rolls and supply for aligning and centering said envelopes while being conveyed, and means pressing on said envelopes during their entire passage through said last-mentioned means to prevent any lift thereof. 20 25

In testimony whereof, I have hereunto signed my name in the presence of two subscribing witnesses.
